WARM AIR REGISTER

Norman Burlin Watkins, Wichita, Kans., assignor to The Coleman Company, Inc., Wichita, Kans., a corporation of Kansas

Application January 29, 1954, Serial No. 28,743

Term of patent 14 years

(Cl. D81—21)

Fig. 1 is a top plan view of a warm air register showing my new design,

Fig. 2 is a front view in elevation, and

Fig. 3 is a side view in elevation.

I claim:

The ornamental design for a warm air register, as shown.
